DEVICE FOR COMPACTING POWDERS

Ernest L. Gooden, Washington, D. C., assignor to
Claude R. Wickard, as Secretary of Agriculture of the United States of America, and his
successors in office

Application December 31, 1940, Serial No. 372,523
1 Claim. (Cl. 226—71)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

Methods of compaction commonly used for granular materials involve either (1) settling by vibration, or (2) compaction of the whole mass at once by the use of pressure, or a combination of (1) and (2).

The essential idea underlying the present invention is the provision of a means that is more efficient than any of the above, with special regard to such very fine powders as are difficult or impossible to compact by vibration and with special regard to the production of such relatively tall columns of compacted materials as are impossible or difficult to produce with uniform porosity throughout the column height by the use of a single application of vertical pressure. The compactor invented by me builds up within a vertical tubular container a column of compacted powder of any desired height, the compacting process proceeding from bottom to top concurrently with the deposition of the material.

In the accompanying drawing, Fig. 1 is a longitudinal section of an assembly consisting of the compacting device, the sample tube within which the powder is to be compacted, and a funnel attached to the sample tube for ease of loading. Fig. 2 is a sectional projection of the same assembly viewed as indicated by the arrows 2, 2 in Fig. 1. Similar numerals refer to similar parts throughout the views.

The compactor, as shown in the accompanying Fig. 1, is a plunger consisting of two parts—a rod or stem 1 and a foot 2. The rod, which appropriately may be of a piece of stiff wire between one and two millimeters in diameter, has kinks distributed practically throughout its length, except a space of several centimeters near the top reserved as a handle 3. On the bottom end of the rod is impaled or attached the foot 2, shown

in longitudinal section in Fig. 1 and in cross section in Fig. 2. The foot is made of rubber or other suitable material, in the general shape of a solid right circular cone frustum with a portion (less than half) cut away on one side. The bottom of the foot (before removal of the segment) must fit smoothly inside the tubular container in which the column of compacted material is to be formed. An example of a container in which it may be desired to form a column of compacted powder is a sample tube 4 for air permeation experiments, with a porous plug 5 serving as a support for the powder.

In use, the compactor is stood up in the empty tube, to the top of which a loading funnel 6 may be closely connected by a short piece of rubber tubing 7. The powder is poured in on top of the compactor foot. Then the plunger is alternately raised and lowered in short strokes and meanwhile twirled slowly between thumb and forefinger, so that the powder gradually works down past the foot, which packs the bed as fast as it is formed. The kinks in the stem assist in feeding the powder and guard against clogging. The rotating motion serves both to increase the effectiveness of the kinks and to prevent compactional inequality due to the failure of the foot to cover the whole cross section of the tube. When the bulk of the material has been packed in place the plunger may be used to scrape down any powder left clinging to the wall of the tube.

Having thus described my invention, what I claim for Letters Patent is:

A device for compacting powdered materials, comprising a stem and an attached foot, the stem provided with kinks to assist in feeding the material, and the foot in the general shape of a solid right circular cone frustum with a segment cut away on one side to form a passage for the uncompacted material, the basal diameter of the foot being only slightly smaller than the inside diameter of the cylinder in which the material is to be compacted.

ERNEST L. GOODEN.
